UNITED STATES PATENT OFFICE

WALTER M. SCHWARTZ, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

PANEL FOR DRIERS

Application filed July 20, 1928. Serial No. 294,254.

This invention relates to improvements in panels used as the enclosing walls of drying apparatus, and particularly the walls of driers in which heated air is circulated.

In constructing this type of drier it has been the practice to provide a heavy framework for the support of all the operating elements or machinery of the drier, including bearings for the mounting of operating shafts, rails for the support of conveyers, fan mountings, and to provide a casing around this framework composed of a plurality of panels which form the walls and roof of the casing.

These walls or panels have heretofore been of a comparatively light construction, comprising a pair of metallic sheets spaced apart and filled with an insulating material, non-conductive of heat.

The object of the present invention is to dispense with the above mentioned separate heavy framework of the drier and to construct at least a portion of the number of panels employed in the formation of the walls of the drier casing in a manner to provide the necessary rigidity to enable these panels to support the above mentioned operating elements of the drier, and the roof thereof.

Another object of the invention is to provide a suitable sealing element between the stationary and removable panels, or between two adjacent stationary panels to prevent the heat from escaping from the interior of the casing.

The construction of the panels will be more fully disclosed hereinafter, reference being had to the accompanying drawings, of which:

Fig. 1 is a face view of what may be termed a stationary panel;

Fig. 2 is a rear view of the panel shown in Fig. 1;

Fig. 3 is a sectional view taken on the line 3—3, Fig. 1;

Fig. 4 is a sectional view taken on the line 4—4, Fig. 1;

Fig. 5 is a face view of what may be termed a removable panel;

Fig. 6 is a rear view of the panel shown in Fig. 5;

Fig. 7 is a sectional view taken on the line 7—7 of Fig. 5;

Fig. 8 is a sectional view taken on the line 8—8, Fig. 5;

Fig. 9 is a front elevation of one of the 55 stationary panels secured to the cap and sill of a drier;

Fig. 10 is a sectional elevation taken on the line 10—10, Fig. 9;

Fig. 11 illustrates one method of securing a 60 removable panel to a stationary panel;

Fig. 12 illustrates a method of connecting two stationary panels, such as in the roof or side wall construction;

Fig. 13 is a front view of a stationary panel 65 showing a method of attaching outside bearings or other fixtures to the panel;

Fig. 14 is a sectional plan view taken on the line 14—14, Fig. 13;

Fig. 15 is a sectional elevation taken on 70 the line 15—15, Fig. 13;

Fig. 16 illustrates a method of securing a rail or track to the panel; and

Fig. 17 is a perspective view of a detail of 75 the invention.

The stationary panel A shown in Figs. 1 to 4 inclusive comprises a pair of Z-bars 1, 1 which form the main longitudinal side or edge members of the panel; a pair of transversely extending L-bars 2, 2 which form the main end members of the panel; a face plate 3; a rear plate 4; a pair of transversely extending Z-plates 5, 5 which are supplementary to the end bars 2, 2 and are located one at each end of the panel; and a body of insulating material 6 confined between the front plate 3, rear plate 4, side Z-bars 1, and end Z-plates 5.

The movable panel B shown in Figs. 5 to 8 inclusive comprises a pair of L-bars 11, 11, which form the main longitudinal side members of the panel; a pair of transversely extending end L-bars 12, 12, which form the main end members of the panel; a face plate 13; a rear plate 14; a pair of transversely extending supplementary Z-plates 15, 15 located one at each end of the panel; a pair of supplementary Z-plates 17, 17 located one at each side of the panel; and a body of insulating material 16 confined between the end and 100

side Z-plates 15, 15 and 17, 17 respectively and the face and rear plates 13 and 15 respectively.

The elements constituting the panels A and B are assembled and secured together in the manner disclosed in the co-pending application of Walter M. Schwartz, Alma J. Harrison and John L. Fagan, filed May 1, 1928, Serial No. 274,309.

10 The Z-bars 1 of the stationary panels A comprise parallel webs 1^b and 1^c connected by a web 1^d extending at right angles to the webs 1^b, 1^c. The web 1^b is provided with a flange 1^a which extends inwardly of the panel and parallel to the web 1^d.

15 A sealing element 20, comprising a strip of cork in the present instance, is mounted in the channel formed by the flange 1^a, web 1^b and web 1^d. The flange 1^a is crimped at intervals, as indicated at 21, Figs. 4 and 17, to keep the strip 20 in place.

20 The outer face 22 of the strips 20 at each side of the panel A lie in a plane α located substantially equidistant from and between the face and back plates 3 and 4 respectively.

25 The L-bars 2 at each end of the panel comprise a web 2^c which lies in a plane coincident with the plane of the webs 1^c of the Z-bars 1, and is provided with an inwardly extending flange 2^a.

30 A sealing element 20^a is positioned in the channel formed by the flange 2^a of the L-bar 2, the web 5^b of the end Z-plate 5 and the web 5^d thereof. The inner face 22^a of the sealing strip 20^a lies in a plane coincident with the outer face 22 of the strips 20 carried by the Z-bars 1, 1.

35 The side or edge L-bars 11 of the removable panels B comprise a web 11^b having a flange 11^a projecting inwardly of the panel, and the end L-bars 12 of the removable panels B comprise a web 12^b lying in a plane coincident with the plane of the webs 11^b of the side bars 11, and are each provided with an inwardly extending flange 12^a.

40 A sealing element 30 is placed in the channel formed by the flange 11^a of the side L-bars 11, the web 17^a of the side Z-plate 17 and the web 17^d thereof, with its inner face 32 lying in a plane α^1 , substantially equidistant from and between the face and rear plates 13 and 14 respectively.

45 A sealing element 30^a is placed in the channel formed by the flange 12^a of the end L-bars 12, the web 15^a of the end Z-plates 15 and the web 15^d thereof, the inner face 32^a of the sealing element 30^a lying coincident with the plane α^1 of the strips 30, 30.

50 Thus it will be seen that the removable panel B is provided with a channel extending completely around the same, at the face thereof adjacent the face plate 13; while the stationary panel A is provided with a channel at each of its opposite ends at the face thereof adjacent the face plate 3, and is pro-

vided with a channel at each longitudinal side edge adjacent the back plate 4 of the panel.

55 The inner faces 22^a of the sealing strips 20 in the end channels of the stationary panels A, and the outer faces 22 of the sealing strips 20 in the longitudinal channels thereof, as above noted, lie in the plane α which extends substantially through the center of the panel A between the face and rear plates thereof.

60 The inner faces 32 and 32^a of the sealing strips 30 and 30^a in the channels of the removable panels B, as above noted, lie in the plane α^1 , which extends substantially through the center of the panel B, between the face and rear plates thereof.

65 When the panels are assembled to form a complete drier casing these planes α and α^1 of the panels A and B respectively, are coincident one with the other, to form a seal to prevent the heated air from escaping from the interior of the casing through the side walls thereof.

70 In assembling the panels to form the casing a plurality of the stationary panels A are secured to one flange 26^a of a longitudinal cap beam 26, at their respective upper edges by bolts 33, and at their respective lower edges to knee plates 34 by bolts 35, see Figs. 9 and 10. The knee plates 34 are secured to sill beams 27 by rivets 36, in the present instance.

75 Secured to and spaced apart from the cap beam 26 is a sealing bar 28 against one flange 28^a thereof the faces 22^a of the sealing strips 20^a at the upper ends of the stationary panel A, A, are adapted to bear.

80 Secured to and spaced apart from the sill beam 27 is a sealing bar 29 against one flange 29^a thereof the faces 22^a of the sealing strips 20^a at the lower ends of the panels A, A are adapted to bear.

85 As shown in Fig. 10 the outer face 22 of the vertical sealing strip 20 of the stationary panel A is coincident with the planes of the flanges 28^a and 29^a of the sealing bars 28 and 29 respectively.

90 The removable panels B are adapted to be secured in place between two spaced stationary panels with the inner faces 32 of their vertical sealing strips 30 in sealing engagement with the outer faces 22 of the sealing strips 20 of the stationary panels A, and the inner faces 32^a of their horizontal sealing elements 30^a in sealing engagement with the flanges 28^a and 29^a of the cap and sill sealing bars 28 and 29 respectively, thus a complete seal between the panels of the walls of the drier casing is obtained.

95 In order to secure the removable panels B in place, clamps 40 are employed as shown in Fig. 11. The heel 41 of each clamp 40 rests against the web 1^c of one of the Z-bars 1 of a stationary panel A and the toe 42 of each

clamp rests against the web 11^b of the L-bar 11 of an adjoining removable panel B.

The clamps 40 are held in place by bolts 43 having heads 43^a which are adapted to be placed in square holes 44 formed in the webs 1^c of the Z-bars 1 and forced into the body of insulating material 6 of the panel, and thereafter moved into slots 45 which respectively project from the holes 44, in the manner and form of a "bayonet" joint. The bolts 43 are secured to the Z-bars 1 by lock nuts 46, and project through the clamps 40, being provided with wing nuts 47 by which the panels may be forced into tight sealing contact with each other.

In Fig. 12, I have illustrated the method of forming a seal between adjacent edges of two adjoining stationary panels A, A, providing a joint plate 24 provided with a channel to receive a sealing strip 25 in the manner shown.

Figs. 13, 14 and 15 illustrate one method of securing a bearing to the fixed panel. In this instance 49 illustrates a portion of the base of a bearing, and on the inner side of the panel are angle bars 50 which are connected to the base 49 by through bolts 51 which pass through sleeves 52. Nuts 53 fasten the bolt to the angle bars 50 and the inner plate 23 of the panel, and the sleeves 52 extend into an opening in the outer plate, so that the base 49 of the bearing rests directly against the sleeves. Nuts 54 firmly clamp the bearing to the sleeves and the angle bars. These angle bars extend from one side of the panel to the other and are attached directly to the heavy Z-beam members 1, 1 of the panel, so that the bearings are supported by these heavy Z-shaped channel members through the medium of the angle bars 50, 50 and their bolts.

Fig. 16 illustrates a method of attaching the longitudinal rails, which are located within the drier, to the heavy Z-bars of the stationary panels. On these panels are angle bars 55 which are bolted to the Z-beams as shown, and supported by these panels are rails 56 which are angular in cross-section and are secured to the bars 55 or other fastenings.

In Figs. 9 and 10, I have shown one of the panels of which the roof is composed. In the formation of the roof, stationary panels may be used throughout or they may alternate with removable panels in the same general manner as in the wall of the drier.

On the roof construction the sealing strips at the ends of the panels rest on the flange 28^b of the cap seal bar 28, the panels proper being secured to the cap beams 26 in any suitable manner.

Thus, it will be seen that I simplify the construction of driers of this type by making the edge members of the stationary panels of heavy material which will not only hold the panels from warping, but will support any

mechanisms attached to these panel members, dispensing with a great number of parts which were heretofore necessary to support the different structural parts of the drier but which are now supported entirely by the vertical Z-bars 1 of the fixed panels.

I claim:

1. A panel constituting in itself a complete hollow-wall section for driers and like apparatus, said panel comprising a pair of Z-shaped longitudinal edge bars; and a pair of metal walls spaced apart and extending in substantially parallel planes between said Z-bars and respectively connected along their oppositely disposed longitudinal edges to said Z-bars, said Z-bars being of a relatively heavy cross-section and adapted to support the machinery of the drier.

2. A panel constituting in itself a complete hollow-wall section for driers and like apparatus, said panel comprising a pair of Z-shaped longitudinal edge bars; a pair of metal walls spaced apart and extending in substantially parallel planes between said Z-bars and respectively connected along their oppositely disposed longitudinal edges to said Z-bars, said Z-bars being of a relatively heavy cross-section and adapted to support the machinery of the drier; and heat insulating material located between said metal walls.

3. A panel constituting in itself a complete hollow-wall section for driers and like apparatus, said panel comprising a pair of Z-shaped longitudinal edge bars; and a pair of metal walls spaced apart and extending in substantially parallel planes between said Z-bars and respectively connected along their oppositely disposed longitudinal edges to said Z-bars, said Z-bars being of a relatively heavy cross-section and adapted to support the machinery and the roof of the drier.

4. A panel constituting in itself a complete hollow-wall section for driers and like apparatus, said panel comprising a pair of Z-shaped longitudinal edge bars; a pair of metal walls spaced apart and extending in substantially parallel planes between said Z-bars and respectively connected along their oppositely disposed longitudinal edges to said Z-bars, said Z-bars being of a relatively heavy cross-section and adapted to support the machinery of the drier; and means secured to the said Z-bars adapted to support machinery elements of the drier.

5. A panel for driers and like apparatus, comprising a pair of Z-shaped longitudinal edge bars; and a pair of metal walls spaced apart and connected to said Z-bars, said Z-bars being of a relatively heavy cross-section and adapted to support the machinery of the drier, each of said Z-bars having a channel formed therein for the reception of a sealing element.

6. A panel for driers and like apparatus,

comprising a pair of Z-shaped longitudinal edge bars; a pair of metal walls spaced apart and connected to said Z-bars, said Z-bars being of a relatively heavy cross-section and adapted to support the machinery of the 5 drier; an end bar extending between and secured to the said Z-bars at each end of the panel; an inturned flange on each end bar; an inturned flange on each Z-bar; said flanges forming channels at the edges of the panel 10 for the reception of sealing elements; and sealing strips in said channels.

7. A panel for driers and like apparatus, comprising a pair of Z-shaped longitudinal edge bars; a pair of metal walls spaced apart 15 and connected to said Z-bars, said Z-bars being of a relatively heavy cross-section and adapted to support the machinery of the drier; an end bar extending between said Z-bars at each end of the panel; an inturned flange on each of said Z-bars adjacent one face of the panel; an inturned flange on each end bar adjacent the opposite face of the panel; said inturned flanges forming channels 20 at the edges of the panel; and sealing elements in said channels the inner faces of 25 said sealing elements lying substantially in a common plane intermediate the opposite faces of the panel.

8. A panel for driers and like apparatus, comprising a pair of Z-shaped longitudinal edge bars; a pair of metal walls spaced apart and connected to said Z-bars, said Z-bars being of a relatively heavy cross-section and 30 adapted to support the machinery of the drier, said panel having a channel formed at and extending across each end thereof adjacent one wall of the panel, and a channel formed at and extending along each of the 35 longitudinal edges of the panel adjacent the opposite wall of the panel; and sealing strips in the respective channels extending toward the center of the panel and terminating in a common plane intermediate the opposite 40 walls of the panel.

9. A wall construction for driers and like apparatus, comprising a plurality of stationary panels and removable panels; each stationary panel comprising a pair of Z-shaped 45 longitudinal edge bars; and a pair of metal walls spaced apart and connected to said Z-bars, said Z-bars being of a relatively heavy cross-section and adapted to support the machinery of the drier, said panel having a channel formed at and extending across each end thereof adjacent one wall of the panel, and a channel formed at and extending along each of the longitudinal edges of the panel adjacent the opposite wall of the panel; and 50 sealing strips in the respective channels extending toward the center of the panel and terminating in a common plane intermediate the opposite walls of the panel; sealing bars extending respectively along the upper and lower edges of said stationary panels and 55 sealing strips in the upper and lower channels respectively; the removable panels of said wall being provided with a channel extending completely around the panel adjacent one face thereof; sealing strips in the channels of said removable panels extending toward the centers of the panels and adapted to engage the sealing strips on the 60 upper and lower edges of said stationary panels and 65 sealing strips in the upper and lower channels respectively; the removable panels of said wall being adapted to engage the sealing strips in the upper and lower channels respectively; the removable panels of said wall being provided with a channel extending completely around the panel adjacent one face thereof; sealing strips in the channels of said removable panels extending toward the centers of the panels and adapted to engage the sealing strips on the 70 upper and lower edges of said stationary panels.

10. A wall construction for driers and like apparatus, comprising a plurality of stationary panels and removable panels; each stationary panel comprising a pair of Z-shaped longitudinal edge bars; and a pair of metal walls spaced apart and connected to said Z-bars, said Z-bars being of a relatively heavy cross-section and adapted to support the machinery of the drier, said panel having a channel formed at and extending across each end thereof adjacent one wall of the panel, and a channel formed at and extending along each of the longitudinal edges of the panel adjacent the opposite wall of the panel; and sealing strips in the respective channels extending toward the center of the panel and terminating in a common plane intermediate the opposite walls of the panel; sealing bars extending respectively along the upper and lower edges of said stationary panels and engaging the sealing strips in the upper and lower channels respectively; the removable panels of said wall being provided with a channel extending completely around the panel adjacent one face thereof; sealing strips in the channels of said removable panels extending toward the centers of the panels and adapted to engage the sealing strips on the 75 upper and lower edges of said stationary panels.

11. A wall construction for driers and like apparatus, comprising a plurality of stationary panels and removable panels; each stationary panel comprising a pair of Z-shaped longitudinal edge bars; and a pair of metal walls spaced apart and connected to said Z-bars, said Z-bars being of a relatively heavy cross-section and adapted to support the machinery of the drier, said panel having a channel formed at and extending across each end thereof adjacent one wall of the panel, and a channel formed at and extending along each of the longitudinal edges of the panel adjacent the opposite wall of the panel; and sealing strips in the respective channels extending toward the center of the panel and terminating in a common plane intermediate the opposite walls of the panel; sealing bars extending respectively along the upper and lower edges of said stationary panels and engaging the sealing strips in the upper and lower channels respectively; the removable panels of said wall being provided with a channel extending completely around the panel adjacent one face thereof; sealing strips in the channels of said removable panels extending toward the centers of the panels and adapted to engage the sealing strips on the 80 upper and lower edges of said stationary panels.

12. A wall construction for driers and like apparatus, comprising a plurality of stationary panels and removable panels; each stationary panel comprising a pair of Z-shaped longitudinal edge bars; and a pair of metal walls spaced apart and connected to said Z-bars, said Z-bars being of a relatively heavy cross-section and adapted to support the machinery of the drier, said panel having a channel formed at and extending across each end thereof adjacent one wall of the panel, and a channel formed at and extending along each of the longitudinal edges of the panel adjacent the opposite wall of the panel; and sealing strips in the respective channels extending toward the center of the panel and terminating in a common plane intermediate the opposite walls of the panel; sealing bars extending respectively along the upper and lower edges of said stationary panels and engaging the sealing strips in the upper and lower channels respectively; the removable panels of said wall being provided with a channel extending completely around the panel adjacent one face thereof; sealing strips in the channels of said removable panels extending toward the centers of the panels and adapted to engage the sealing strips on the 85 upper and lower edges of said stationary panels.

longitudinal edges of the stationary panels and the sealing bars intermediate the stationary panels; and means for securing the removable panels in place.

- 5 12. A wall construction for driers and like apparatus, comprising a plurality of stationary panels and removable panels; each stationary panel comprising a pair of Z-shaped longitudinal edge bars; and a pair of metal walls spaced apart and connected to said Z-bars, said Z-bars being of a relatively heavy cross-section and adapted to support the machinery of the drier, said panel having a channel formed at and extending across each end thereof adjacent one wall of the panel, and a channel formed at and extending along each of the longitudinal edges of the panel adjacent the opposite wall of the panel; and sealing strips in the respective channels extending toward the center of the panel and terminating in a common plane intermediate the opposite walls of the panel; sealing bars extending respectively along the upper and lower edges of said stationary panels and engaging the sealing strips in the upper and lower channels respectively; the removable panels of said wall being provided with a channel extending completely around the panel adjacent one face thereof; sealing strips in the channels of said removable panels extending toward the centers of the panels and adapted to engage the sealing strips on the longitudinal edges of the stationary panels and the sealing bars intermediate the stationary panels; and means for securing the removable panels in place comprising bolts adjacent the edges of the stationary panels and clamp plates on said bolts having a heel engaging the stationary panel and a toe engaging the removable panel. 100
13. A casing construction for driers and like apparatus, comprising a plurality of stationary panels and removable panels; each stationary panel comprising a pair of relatively heavy longitudinal edge bars of Z-shaped cross-sectional form; an end bar extending between and connected to said Z-bars at each end of the panel; a front wall and a rear wall composed of relatively light gage metal connected to said Z-bars and said end bars; an inturned flange on each end bar extending toward the center of the panel from the front wall thereof; an inturned flange on each Z-bar extending toward the center of the panel from the rear wall of the panel; said flanges forming channels at the respective edges of the panel; sealing strips located in said channels; a sill beam secured to the bottoms of said stationary panels; a cap beam secured to the tops of said stationary panels; sealing bars connected to said cap and sill beams respectively and engaging the sealing strips in the respective ends of said stationary panels; said removable panels
14. A casing construction for driers and like apparatus, comprising a plurality of stationary panels and removable panels; each stationary panel comprising a pair of relatively heavy longitudinal edge bars of Z-shaped cross-sectional form; an end bar extending between and connected to said Z-bars at each end of the panel; a front wall and a rear wall composed of relatively light gage metal connected to said Z-bars and said end bars; an inturned flange on each end bar extending toward the center of the panel from the front wall thereof; an inturned flange on each Z-bar extending toward the center of the panel from the rear wall of the panel; said flanges forming channels at the respective edges of the panel; sealing strips located in said channels; a sill beam secured to the bottoms of said stationary panels; a cap beam secured to the tops of said stationary panels; sealing bars connected to said cap and sill beams respectively and engaging the sealing strips in the respective ends of said stationary panels; said removable panels
15. A casing construction for driers and like apparatus, comprising a plurality of stationary panels and removable panels; each stationary panel comprising a pair of relatively heavy longitudinal edge bars of Z-shaped cross-sectional form; an end bar extending between and connected to said Z-bars at each end of the panel; a front wall and a rear wall composed of relatively light gage metal connected to said Z-bars and said end bars; an inturned flange on each end bar extending toward the center of the panel from the front wall thereof; an inturned flange on each Z-bar extending toward the center of the panel from the rear wall of the panel; said flanges forming channels at the respective edges of the panel; sealing strips located in said channels; a sill beam secured to the bottoms of said stationary panels; a cap beam secured to the tops of said stationary panels; sealing bars connected to said cap and sill beams respectively and engaging the sealing strips in the respective ends of said stationary panels; said removable panels
